UNITED STATES PATENT OFFICE.

JAMES M. WELCH, OF VICKSBURG, MISSISSIPPI.

BIT BRACE.

Application filed July 17, 1923. Serial No. 652,147.

The present invention relates to bit braces and has for its principal object to provide a brace of this nature which is extensible so that a greater leverage may be obtained when needed.

Another important object of the invention is to provide an extensible brace of the type described which possesses a simple and efficient construction, one which is reliable in operation, comparatively inexpensive to manufacture, durable, and well adapted to the purpose for which it is designed.

With the above and numerous other objects in view as will appear as the description progresses, the invention resides in certain novel features of construction, and in the combination and arrangement of parts as will be hereinafter more fully described and claimed.

20 In the drawing

Figure 1 is a perspective view of the bit brace embodying my invention.

Figure 2 is a fragmentary elevation of a portion thereof showing the same extended partially,

Figure 3 is a longitudinal section through one leg of the body portion of the brace,

Figure 4 is a similar view showing the parts extended, and

Figure 5 is a transverse section taken substantially on the line 5—5 of Figure 3.

Referring to the drawing in detail it will be seen that the body 1 is of the usual U-shaped structure including the intermediate portion 2 and the legs 3. One leg 3 has its end extended at right angles as at 4 for the reception of a swivelly mounted knob 5. The end of the other leg 3 receives the pawl and ratchet mechanism 6 which is connected with the disengaging member 7. The intermediate portion 2 is provided with a sleeve 8 which rotates thereon. The parts thus far described are all more or less of conventional construction.

45 My invention consists in improving the legs 3 by making them extensible so that a greater leverage may be obtained as is often desirable. I construct the legs 3 in a plurality of telescopically associated sections,

50 and in the present instance have shown three sections by way of example. The inner or first section 9 is provided at its terminal with a head 10 which head is slidable in the

intermediate or second section 11 which is in the form of a tube having an internal 55 longitudinally extending groove 12. Apertures 13 are provided in the second section 11 at each end of the groove 12. A spherical member 14 is disposed in an orifice provided in the head 10 and a spring 15 is tensioned 60 to push this spherical member outwardly so as to engage in the groove and the aperture. This spherical member prevents the intermediate or second section 11 rotating in relation to section 9 but allows the same to 65 slide in relation to each other. A plug 17 is threaded into each end of the second section 11 and one of them is provided with an orifice containing a spherical member 18 and a spring 19. This plug having the orifice 70 is constructed with an enlarged head slideable in the third or outer section 20 which is provided with a longitudinally extending groove and apertures 22 one at each end of the groove. This groove 21 and apertures 75 22 are adapted to receive the spherical member 18 thus preventing the outer section from rotating in relation to the intermediate section 12. These sections 12 and 20 are of similar construction. A plug 24 is disposed 80 in one end of the section 20 and is adapted to abut the head of the plug 17. A plug 25 is threadedly engaged with the other end of the outer section 20 and is connected with the remaining portion of the leg 3.

85 The apertures and grooves mentioned are also useful in feeding oil to the extendible feature of the device. It is thought that the construction and operation of the invention will now be readily understood without a more detail description thereof. In the present instance, I have shown and described only the preferred embodiment of the brace which will give in practice satisfactory and reliable results, and it is to be understood that the same is susceptible of modification in various particulars without departing from the spirit or scope of the invention or sacrificing any of its advantages.

90 Having thus described my invention, what I claim as new and desire to secure by Letters Patent, is:

95 An extensible bit brace arm comprising an outer tubular section having a longitudinally extending groove and further provided 100 with apertures at the ends of the groove, a

2

plug in one end of the section, a second plug in the other end of the section having an opening therein, a smaller tubular section inserted through said last named plug and received within the outer section, a plug carried by the inner end of the inner section, and means carried by the last named plug and slidably received within the said

groove whereby to prevent the rotation of the inner section relative to the outer section, said means adapted to be received within the said aperture to lock the arm either in extensible or collapsed position. 10

In testimony whereof I affix my signature.

JAMES M. WELCH.
